UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,908, dated November 29, 1887.

Application filed October 15, 1887. Serial No. 252,505. Term of patent 3½ years.

To all whom it may concern:

Be it known that I, HENRIETTA F. DUKE, of the city, county, and State of New York, have invented and produced a new and original Design for a Pattern of a Lady's Costume; and I do hereby declare that the engraved prints accompanying this specification, convey to any one accustomed to using paper patterns a clear understanding of how a garment made up by the pattern will appear.

The design shows a close-fitting basque and a round walking skirt. The skirt displays a full right-side drapery that exhibits draping plaits in its back edge and a fullness at its front edge, where it extends to the lower edge of the skirt; a left-side drapery that overlaps the front edge of the right-side drapery and exhibits two groups of deep kilt-plaits flaring in fan outline from the belt to the lower edge, which comes even with the edge of the skirt; a back drapery that falls even with the edge

of the skirt and displays kilt-plaits flaring in fan fashion all the way down the center, and a plain side that exhibits soft wrinkles at the top. The basque displays an under-folded 25 double box-plait below the waist-line of its center seam, extra fullness below the waist-line of each side back seam, a high standing collar, and coat sleeves. The outline of the basque describes a point at the center of the 30 front, a high arch at the sides, and a point at the center of the back.

What I claim as my invention, and desire to secure by Letters Patent, is—

The design for a lady's costume, as shown 35 in the engraved prints accompanying this specification.

HENRIETTA F. DUKE.
